UNITED STATES PATENT OFFICE.

JOSEPH SPOONER AND EBENEZER SPOONER, OF NEW YORK, N. Y.

IMPROVEMENT IN TUBULAR PAPER-BOX CUTTERS.

Specification forming part of Letters Patent No. 94,358, dated August 31, 1869.

To all whom it may concern:

Be it known that we, JOSEPH SPOONER and EBENEZER SPOONER, of New York city, in the county and State of New York, have invented a new and Improved Machine for Cutting Tubular Paper Boxes; and we do hereby declare that the following is a full, clear, and exact description thereof, which will enable others skilled in the art to make and use the same, reference being had to the accompanying drawings, forming part of this specification, in which—

Figure 1 is a top or plan view of our improved machine. Fig. 2 is a front view of the same, part of the knife-plate being broken away to show the construction. Fig. 3 is a detail sectional view of the knife-table. Fig. 4 is a detail view, showing the manner in which the free end of the swinging roller is secured in its bearings. Fig. 5 is a detail view of the swiveled bearings of the other end of the roller.

Similar letters of reference indicate corresponding parts.

Our invention has for its object to furnish an improved machine by means of which tubular paper boxes may be cut from tubular paper rolls conveniently, rapidly, and accurately, and which shall be simple in construction and easily and conveniently operated; and it consists in the construction and combination of various parts of the machine, as hereinafter more fully described.

A is the bed-plate of the machine, which is supported upon a bench or suitable framework, and to which, at or near its ends, are attached the standards that support the roller.

Upon the upper surface of the bed-plate A are formed or to it are attached ways a' , which enter grooves in the under side of the plate B, so that the said plate B may have a longitudinal movement upon said ways a' . The plate B is held steadily in place while the machine is being used by the set-screws b' , which pass through the roller-standards, and the forward ends of which press against the end edges of the said plate B, as shown in Figs. 1 and 2.

Upon the upper side of the plate B, near its front and rear sides, are formed or to it are attached transverse ways b^2 , which enter grooves upon the under side of the plate C, so that the said plate C may move freely back and forth.

To the plate C are attached upwardly-pro-

jecting bolts or standards D, upon the upper ends of which are cut screw-threads to receive the nuts d' , which are placed the one above and the other below the knife plate or table E to adjustably connect the said plate E to the plate C. The plate or table E is slotted longitudinally, and upon its under side, just beneath the said slot, is formed a groove or channel, e' , which is also slotted longitudinally, as shown in Fig. 3.

F are circular revolving knives, which are pivoted in the slotted upper ends of the standards G, the lower ends of which fit into the slots in the plate E.

H are set-screws screwing through sliding blocks I, placed in the groove or channel e' of the plate E, and the upper ends of said screws enter recesses formed in the lower ends of the standards G for the more delicate adjustment of the knives, the main adjustment of said knives being made with the nuts d' upon the bolts D. The standards G are kept at the desired distance apart by the blocks J, placed between them, and which may be made with tongues or tenons to enter the slot of the plate E, a different set of blocks being used for each different size of box to be cut. The knife-standards G and blocks J are clamped together and held in their proper position by set-screws K, passing in through ears e^2 , attached to the plate E, and the forward ends of which rest against the end standards, G, or against blocks J, placed at the outer sides of said standards G. By this construction the knives can be very quickly and easily adjusted, according to the size of the box to be cut. The plate E may be moved forward to cause the knives to bear against the roller by a treadle or other convenient and well-known means, and may be drawn back to withdraw the said knives from the said roller by a suspended weight or spring or other convenient means.

L is the roller, which is made of iron, brass, or other metal, and the journals of which revolve in bearings M and N, attached to or formed in the upper ends of the standards O, the lower ends of which are attached to the plate A. The bearing M is a horizontal slot formed in the upper end of one of the standards O, and the journal of the roller is kept in place by a pin, P, passing vertically through said bearing in front of said journal, as shown in Figs. 1, 2, and 4. The other bearing, N, is

swiveled to the upper end of the other standard O. By this construction, by simply removing the pin P, the end of the roller L may be swung forward, so that the paper roll may be conveniently placed upon or the cut boxes removed from the roller L. The roller L is revolved, in cutting the boxes, by a crank attached to the projecting end of the journal at the swiveled end of said roller.

We claim as new and desire to secure by Letters Patent—

1. The combination, with a set of paper-cutters arranged at suitable intervals on a revolving shaft, of a roller, L, swinging round on a pivot at one end to receive the paper tube, and rotating in its bearing so as to bring the said tube into contact with the cutters, all as shown and described.

2. Swiveling one end of the roller upon

which the paper roll is placed to be cut to its supporting-standard in such a way that its other end may be swung outward, as and for the purpose set forth.

3. An improved machine for cutting paper boxes, formed by the combination of the adjustable plates B and C, adjustable knife-plate E, adjustable knife-standards G, adjusting blocks J, circular revolving knives F, and swiveled roller L with each other and with the bed-plate A and standards O, substantially as herein shown and described, for the purpose set forth.

J. SPOONER.
